UNITED STATES PATENT OFFICE.

MATT J. JELEN, OF CHICAGO, ILLINOIS, ASSIGNOR TO STEWART-WARNER CORPORATION, OF CHICAGO, ILLINOIS, A CORPORATION OF VIRGINIA.

RADIORECEIVER.

Application filed July 20, 1928. Serial No. 294,107.

- Among the objects of my invention are the provision of a means for effectively controlling volume, a means for controlling regeneration and a means for coordinating these two controls so that they may be adjusted simultaneously by a single operation. In the modern highly perfected radio receiver, it is essential that there should be an effective volume control which will operate without disturbing the working voltages, the tuning of the various circuits, etc. It is also essential that control of regeneration should be had by some means both effective and simple to operate. A third requirement is that there should be few manually operated controls and that the set should be made as automatic and "fool-proof" as possible.
- By my invention I control both volume and regeneration by means of a single manual adjustment. The actual tuning of the set may also be controlled by a single manual adjustment through mechanical coupling of the tuning condensers of the various stages in the well known manner.
- Referring to the drawings:
- Fig. 1 is a wiring diagram of a radio receiving circuit illustrating a volume control in the form of a resistance in the antenna circuit.
- Fig. 2 is a similar diagram with the addition of a regeneration control in one of the grid circuits, and
- Figs. 3 and 4 are similar diagrams illustrating two ways in which these controls may be combined into an operatively single unit in accordance with my invention.
- A means by which a convenient and smooth acting control of volume may be had without otherwise affecting the receiver, is illustrated in Figure 1 of the accompanying drawings, in which is shown the first stage of a radio frequency amplifier and part of the second stage of generally conventional form. The antenna 1 is coupled to the circuit of the first radio frequency tube 2 by the usual coupling transformer 3. The second stage is coupled to the first in the usual manner by means of transformer 4. Control of volume is effected by a variable resistor 5 connected in parallel with the primary winding 6 of transformer 3. By changing the effective resistance of resistor 5, a greater or less amount of the energy picked up by the antenna will be by-passed to the ground around the primary winding 6. The higher the effective resistance of resistor 5 is made the less energy will be by-passed and vice versa. By this means the amount of energy permitted to pass through the primary 6 of transformer 3 and, consequently, the amount of energy which will be fed to the grid of audion 2, can be varied over a wide range and a simple and efficient control of volume obtained.
- Regeneration may be controlled by increasing or decreasing the resistance in the grid circuit of one of the stages of the amplifier. Increasing the resistance will reduce the amount of regeneration whereas decreasing the resistance will permit of a greater degree of regeneration. A successful and simple regeneration and partial volume control based upon this principle is illustrated by Figure 2 which shows a circuit generally similar to that of Figure 1 with the exception that in the grid return lead of audion 8 has been inserted a variable resistor 7 in series with the secondary winding of transformer 4. The amount of regeneration may be reduced by increasing the effective value of resistor 7 and vice versa.
- From the above it is apparent that the amount of energy delivered to the receiver from the antenna and, consequently, the volume of the sounds delivered to the loud speaker may be controlled by varying the effective value of resistance 5. Also that the amount of regeneration may be controlled by varying the effective value of resistor 7. It will also be evident that the effect of the two resistances are opposite, that is to say, an increase in the effective value of resistance 5 results in an increase in the amount of energy delivered to the first tube, whereas an increase in the effective value of resistance 7 results in a decrease in regeneration. This being so, both the volume control and the regeneration control may be combined into a single unit, namely, a single resistance with a single variable element so that they may both be simultaneously adjusted by a single operation.
- One application of my invention is illustrated by Figures 3 and 4 in the accompanying drawings. In Figure 3 it will be seen that the volume control shown in Figures 1 and 2, namely, a variable resistance 5 in parallel with the primary winding 6 of transformer 3 has been used. The regeneration control shown in Figure 2 which comprises a variable

resistance 7 associated with the secondary of transformer 4 has also been retained. However, in this instance, the two resistances 5 and 7 have been combined into a single resistance with a single variable element 9. Since one end of the variable resistance is connected to the grid return of tube 8 and the other end to the antenna side of winding 6 of transformer 3, any adjustment of variable 5 arm 9 will cause a change in resistance, both in the volume control circuit and in the regeneration control circuit. When the resistance in the volume control circuit is increased, the resistance in the regeneration control will be 10 decreased and vice versa. It will be readily apparent to those skilled in the art that, for the effective operation of a radio receiver, regeneration should be increased for weak signals and decreased for strong signals. By 15 the method which I have invented and described, the control of volume and regeneration is accomplished in accordance with this principle by a single operation.

Figure 4 illustrates a modification of my 20 invention as shown in Figure 3 which permits of an independent preliminary adjustment of the effective values of resistors 5 and 7 to meet the varying conditions encountered by radio receivers. Here the resistors 5 and 25 7 are not combined into a single resistance as in Figure 3, but are kept separate as in Figures 1 and 2. Also each has its own adjustable arm 10 and 11 by means of which a greater or less proportion of each resistance 30 35 may be included in the circuit. These two arms 10 and 11, however, are electrically connected to each other and to the conductor 12 through a common lead 13. In operation, arms 10 and 11 are locked together by any 40 convenient means so that they may be adjusted simultaneously by means of a single control. Arms 10 and 11 may, however, be individually adjusted so that the ratio of resistance 5 to resistance 7 may be regulated to 45 suit the desired conditions of volume and regeneration. Individual adjustment may be made possible by securing arms 10 and 11 to their common shaft by means of set screws or in any other convenient manner.

50 I do not intend to limit my invention to the exact arrangement of parts and circuits described. It will be evident to those skilled in the art that my invention may be employed in many other circuits without departing from 55 its essential features.

I claim:

1. A radio receiving circuit including a multi-electrode audion, a tuned grid circuit therefor, means for coupling said grid circuit to 60 an antenna circuit, variable means associated with said antenna circuit for by-passing to

ground more or less of the energy received, variable means in said grid circuit for controlling regeneration, and means whereby adjustment of said by-passing means will 65 cause a concurrent automatic adjustment of said regeneration control.

2. A radio receiver, comprising two or more multi-electrode audions in cascade, an antenna circuit coupled to the grid circuit of 70 the first audion, means associated with said antenna circuit for by-passing to ground any part of the energy therein, means associated with a grid circuit for controlling regeneration, said by-passing and regeneration controlling means being concurrently operable 75 by a single control.

3. A radio receiving circuit including two or more multi-electrode audions in cascade, an antenna circuit coupled to the grid circuit 80 of the first audion, a variable resistance in parallel with said antenna circuit for by-passing to ground any part of the energy therein, a variable resistance in a grid circuit for controlling regeneration, and means whereby 85 said variable resistances may be concurrently varied by a single control.

4. In a radio receiving circuit employing multi-electrode audions, a combined volume and regeneration control comprising a resistance in parallel with the antenna circuit, a resistance associated with a grid circuit, a movable element for each resistance for varying the effective resistance of one in inverse relation to that of the other, said movable 95 elements being concurrently operated as a unit by a single control.

5. In a radio receiving circuit employing multi-electrode audions, a combined volume and regeneration control comprising a resistance in parallel with the antenna circuit, a resistance associated with a grid circuit, a movable element for each resistance for varying the effective resistance of one in inverse relation to that of the other, said movable 100 elements being concurrently operated as a unit by a single control and also being capable of independent adjustment whereby the ratio of the effective resistance of one to that of the other may be varied.

6. In a radio receiving circuit employing multi-electrode audions in two or more transformer coupled stages, a combined volume and regeneration control comprising a variable resistance in parallel with the primary 105 winding of the input transformer, a variable resistance in a grid circuit, means for adjusting the relative effective values of said resistances and unitary means for varying both of said resistances concurrently and inversely.

MATT J. JELEN.
